UNITED STATES PATENT OFFICE.

MATTHEW HARRINGTON, OF SPOKANE, WASHINGTON.

STARTER.

Application filed April 18, 1925. Serial No. 24,109.

To all whom it may concern:

Be it known that I, MATTHEW HARRINGTON, a citizen of the United States, residing at Spokane, in Spokane County, and State 5 of Washington, have invented certain new and useful Improvements in Starters, of which the following is a specification.

My present invention relates to improvements in starters for internal combustion 10 engines, of the type employing an easily-vaporized fluid or gas which is fed to the engine when it is to be started, whereby the initial combustible charges are more readily formed, the engine being afterwards operated by volatile fluid in usual manner.

In carrying out my invention I utilize a valved coupling preferably located in the intake manifold of the internal combustion engine and forming a normally closed permanent fixture. In connection with the coupling I utilize a separate supply device for temporary attachment to the coupling for supplying the initial charges to the engine, and means are provided for automatically opening and closing the valved coupling to the manifold.

The invention consists in certain novel combinations and arrangements of parts as will hereinafter be more fully set forth and 30 claimed.

In the accompanying drawings I have illustrated one complete example of the physical embodiment of my invention wherein one mode is illustrated for carrying out 35 the principles of my invention.

Figure 1 is a view showing a portion of an intake manifold and a carburetor for an internal combustion engine with the device of my invention applied thereto.

Figure 2 is an enlarged detail sectional view of the valved coupling of the manifold showing the actuating nozzle applied thereto.

Figure 3 is a detail of the locking device for the gas spout and gas tank.

Figure 4 is a vertical sectional view of the acetylene gas tank which may be used for supplying the starting gas or charges for the engine.

In carrying out my invention I have shown 50 a carburetor 1 and intake manifold 2 in Figure 1 of usual type, and the manifold or other suitable intake device for the engine cylinders is provided with a permanent coupling 3 in the form of a tubular casting having exterior threads 4 for screwing into complementary threads in the wall of the

manifold, and it will be obvious of course that the coupling is located between the carburetor and the engine.

The inner end of the coupling is provided 60 with a valve seat 5 within the manifold, and this seat is normally closed by an inwardly opening valve 6 having a stem 7 extending outwardly through the coupling. On the outer end of the stem is provided an open 65 head or ring 8 fixed as by a pin 9 to the stem, and this head is slidable in the coupling as the valve is opened or closed, as indicated by dotted lines in Figure 2.

Between the wall of the valve seat 5 in the 70 coupling and the hollow head 8 is interposed a spring 10 coiled about the stem and designed to normally force the head outwardly and hold the valve on its seat. On the outer 75 face of this open head is attached by suitable means a washer or gasket 11 to form a cushion and prevent leak of the starting gas from the coupling.

While any suitable gas may be employed 80 for the starting combustible charge I find that acetylene gas is convenient and may be used with facility.

I prefer to use a portable, hand manipulated generator for the acetylene gas, in the form of a tank or cup 12, which has a top 85 outlet opening and arcuate locking flanges 13 about the opening.

A detachable spout 14 is provided for the tank and the spout is fashioned with arcuate flanges 15 so that the spout may readily 90 be locked to the tank or unlocked therefrom when the tank is not in use.

The spout is of angular shape with a reduced nozzle and on the exterior of the nozzle I provide a hooked shaped lug 16 which 95 is adapted for insertion in the curved flange 17 fashioned at the outer end of the coupling or hollow casting 3. The tank is manipulated by use of the handle 18, and it will be apparent that when the nozzle is entered 100 in the open outer end of the coupling (as indicated by dotted lines in Figure 2 with the hooked-lug in the curved flange) and the nozzle turned down to dotted line position, this action will push in the head 8 and 105 open the valve 6. In this position the valve spring 10 is compressed and gas is permitted to flow through the nozzle and coupling to be sucked into the manifold and engine cylinder. With the ignition system in operation the starting charges are exploded to 110 operate the engine. After the engine is started

the nozzle is withdrawn from the coupling and the valve 6 is automatically returned to its seat, and the engine is operated in usual manner.

5 For generating the acetylene gas in the tank or cup I provide a cage 19 for the calcium carbide and a separate water tank 20 with a water passage 21 to the generating chamber. The generation of gas is controlled by use of a valve 22 having a hand wheel 23 outside the tank for manual control.

10 When not in use the spout is detached from the tank and a closure may be applied 15 to its outlet, and the tank and spout may be carried on an automobile as an accessory. Under normal conditions the valve 6 is closed by its spring and retained in such position against access of air to the manifold.

20 The hollow slide head of the valve stem is normally held within the outer open end of the coupling and protected by the overhanging curved attaching flange 17 for the nozzle of the spout 14, and it will be apparent 25 that this additional element—the coupling—may be attached to the manifold without disturbing the relative arrangement of the

usual feed system for gas to the interior of the engine.

Having thus fully described my invention, what I claim as new and desire to secure by Letters Patent is—

1. The combination with the intake manifold of an internal combustion engine, a coupling fixed thereto, a normally closed valve in said coupling, and means on the coupling for receiving a supply nozzle, of a tank and means therein for generating gas, and a supply nozzle on the tank for co-action with the coupling for opening said valve.

2. The combination with an intake manifold having a laterally extending cylindrical valve casing with a spring pressed normally closed valve having a stem extending through said casing, an annular head on said stem, a curved flange on the outer end of said casing, a supply nozzle adapted for insertion within said casing to move said head for opening the valve, and a lug on said nozzle for guiding engagement under the curved flange of said valve casing.

In testimony whereof I affix my signature.
MATTHEW HARRINGTON.
